HEEL-MAKING MACHINE

Fred Ashworth, Wenham, Mass., assignor to
 United Shoe Machinery Corporation, Borough
 of Flemington, N. J., a corporation of New
 Jersey

Application March 22, 1939, Serial No. 263,453

8 Claims. (Cl. 12—50)

This invention relates to heel-making machines and is exemplified herein as embodied in a machine of the type employing heel assembling apparatus in which pasted lifts are assembled by hand in a form where they are held under pressure, applied by power, while heel building nails are driven through them, the pasted and nailed assembly of lifts then being transferred to a press clamp wherein the heel is held under pressure until the paste has set.

It is an object of the invention to provide an improved machine of this type, the use of which will insure the production of accurate heels of high quality with a minimum requirement for skill and experience on the part of the operator.

With this in view, the illustrated machine embodies heel assembling apparatus and heel pressing apparatus comprising a series of clamps rotatively mounted beside the assembling apparatus, in combination with power means adapted to simultaneously operate the assembling apparatus, rotate the clamps and automatically open one of the clamps for the reception of a heel, together with operator controlled means for closing the opened clamp independently of the power operations. The assembling and pressing apparatus are preferably operated by a common drive shaft, the pressing apparatus comprising a series of spring closed heel clamps upon a carrier which is rotated step by step. A normally stationary cam is arranged to open the clamps automatically in succession as they reach a predetermined point in the movement of the carrier and a treadle connected to said cam permits the operator to move the cam sufficiently to permit the open clamp to close upon a heel, which has been placed therein, while the carrier is stationary.

Another feature of the invention resides in a combined heel gage and ejector arranged to eject a finished heel from a clamp when the clamp is opened and then to retreat to a location in the clamp such that it can be used as a gage to facilitate the correct positioning of a new heel in the open clamp.

A further feature of the invention relates to an improved heel assembling form in which a plurality of heel engaging jaws which extend upward from a table constituting the bottom of the form are bodily compressible in response to downward pressure. This eliminates inaccuracies in lift alinement which are liable to occur with jaws designed to yield outward when the lifts are forcibly pressed down in the form, and retains the advantage that the edges of the lifts are not objectionably marked by their pressure against

the jaws. As illustrated, the jaws are pivotally suspended so that they may be swung transversely of the form in order to adjust the width of the form and the invention includes improved mechanism for effecting such adjustments, comprising pivoted guide arms engaging the lower portions of the jaws and operated by a right and left screw to effect equal and opposite adjustments of the jaws simultaneously to vary the width of the form.

These and other features of improvement will be better understood and appreciated from the following detailed description of an illustrative machine, to be read in connection with the accompanying drawings, in which

Fig. 1 is a view in front elevation of a heel-making machine embodying the invention;

Fig. 2 is a view, partly in section and partly in side elevation, showing details of the heel-pressing mechanism on an enlarged scale;

Fig. 3 is a sectional view taken on the line III—III of Fig. 4 showing further details of the heel-pressing mechanism;

Fig. 4 is a sectional view on the line IV—IV of Fig. 3;

Fig. 5 is a detail sectional view on the line V—V of Fig. 4;

Fig. 6 is a plan view of the heel form in which the heel lifts are assembled; and

Fig. 7 is a vertical sectional view on the line VII—VII of Fig. 6.

The heel assembling and pressing mechanism is mounted in a machine frame 10 having a base 12 and is driven by a suitable source of power connected to a main driving shaft 14. From the shaft 14 power is transmitted to the presser foot 16 and the nail driver, or drivers, 18 by which an assembled pile of heel lifts in a heel form F is placed under pressure and nailed together.

A sprocket 20, fixed upon the shaft 14, is connected by a drive chain 22 to a sprocket 24 secured to a worm shaft 26 upon which is fixed a worm 28. A worm gear 30 secured to a shaft 32 is permanently in mesh with the worm 28 and is driven thereby to rotate the said shaft. The shaft 32 is journaled in stationary bearings 34, 36 and has secured to it by a key 38 the hub 40 of a circular, rotatable carrier 42 (Fig. 4), upon which are mounted the attaching face engaging plates of twelve identical heel pressing clamps.

Journaled upon the hub 40 of the carrier 42, and coaxial therewith, is the hub 44 of a twelve-armed spider 46, which carries the top-lift engaging plates of the said twelve clamps. In as-

much as all of the clamps are identical, it will be sufficient to describe one of them in detail.

Referring to Figs. 2, 3 and 4, a stud 48 fixed in bosses 50, 52, formed on the carrier 42, constitutes a pivot for a lever having three arms 54, 56 and 62. The arm 54 carries an angularly adjustable heel-attaching face-engaging base plate 60 and the arm 56 engages the outer end of a heavy compression spring 62, the inner end of which is seated upon a flat surface 64 formed upon the hub 40 and is held against lateral displacement by a plug 66 set in said hub. The spring 62 supplies all the clamping pressure which is applied to the heel.

The outer end of the lever arm 62 carries a cam roll 70 which cooperates with a cam 72, which has a hub 74 journaled for free rotary movement upon the shaft 32. The cam 72 is normally stationary but is arranged to have a limited amount of rotary movement imparted to it by the operator when desired. To this end a lug 76 projecting radially from the hub 74 is connected by a treadle rod 78 to a treadle 80, which is pivoted at 82 in the machine frame. A pull spring 84, the lower end of which is connected to the treadle and the upper end of which is secured upon a pin 86 fixed in the bearing 38, tends constantly to lift the treadle and turn the cam 72 in a clockwise direction, as viewed in Fig. 2. The limit of clockwise movement of the cam 72 is adjustably determined by a screw 88 threaded through a lug 90 projecting radially from the cam hub 74 and engaging a stationary stop 92 formed upon the machine frame.

Most of the periphery of the cam 72 is concentric with the shaft 32 and the radius of this concentric portion of the cam is sufficiently short so that when a heel is held under pressure in one of the clamps, the cam roll 70 belonging to that clamp will not engage the concentric portion of the cam. A high portion is provided, however, upon the cam to engage the cam roll 70 and open the clamp to release the pressed heel at a certain stage in the rotation of the clamp carrier. This high portion is provided by a suitably shaped plate 94, which is permanently secured to the cam 72. When the cam roll 70 reaches the highest portion of the plate 94, the spring 62 will have been compressed sufficiently to open the clamp far enough to permit the pressed heel to be removed therefrom. This occurs when the cam roll 70 has reached a point near the upper end of the plate 94, as illustrated in Figs. 2 and 3.

After a pressed heel has been removed from the clamp and a fresh heel inserted, it is desired to clamp the new heel before the press starts to rotate and this may be done by depressing the treadle 80, which will cause the cam to be rotated in a counterclockwise direction (as viewed in Fig. 2) a sufficient distance to permit the cam roll 70 to drop off the upper end of the plate 94, allowing the spring 62 to exert its force upon the heel.

Inasmuch as the spring 62 is very stiff, it is desirable to cushion the shock which would occur when it falls off the end of the plate 94. For this purpose there is provided a buffer plate 96 movable about a fixed pivot 98 supported in a stationary bracket 100, which is secured by bolts 102 to the bearing 38. Affixed to the buffer plate 96 and movable therewith about the pivot 98 is an arm 104, to the upper end of which is pivoted a rod 106 which passes loosely through a guide

sleeve 108, adjustably mounted in the bracket 100, and is surrounded by a compression spring 110, one end of which bears against the inner end of the sleeve 108. The tension of this spring may be varied by adjustment of the sleeve in the bracket 100.

When the cam 72 is rotated sufficiently to permit the cam roll 70 to fall off the upper end of the plate 94, the cam roll is in engagement with a surface upon the buffer plate 96, which is a continuation of the cam surface of the plate 94, but the pressure exerted by the stiff spring 62 will cause the plate 96 to be swung toward the right, as viewed in Fig. 2, and the shock will be absorbed by the spring 110.

A top-lift engaging plate 112, which cooperates with the base plate 60 to form a clamp, is pivoted upon a trunnion 114 fixed in the spider 46 and has an inwardly extending arm 116 which engages in a notch 118 in the carrier 42, there being twelve such notches in the carrier, one for each clamp. It will be apparent that a rotary relative adjustment of the spider 46 and the carrier 42 about their common axis will effect an accurate simultaneous adjustment of all of the clamp plates 112, the purpose of which adjustment is to provide for heels of different heights. Provision for making such adjustments is illustrated in Figs. 3, 4 and 5. Two screws 120 and 122 are threaded through the hub 44 of the spider member 46, and their points bear upon blocks 124 and 126 seated in recesses in the hub 40 of the carrier 42. By unscrewing one of these screws and screwing in the other the desired relative rotary adjustment of the spider and the carrier in either direction is effected, and the respective parts are held rigidly in their adjusted relation to each other.

For the purpose of providing a gage to facilitate the correct positioning of a heel in the clamp and to eject a finished heel quickly from the clamp when the clamping pressure has been released, the following mechanism is employed. A pair of arms 128, the lower ends of which are rigidly connected by a crossbar 130, are pivoted at their upper ends upon studs 131 and 133 projecting inward from brackets 134 and 135 secured upon the ends of the trunnion 114 of one clamp, the bar 130 swinging over the plate 112 of the adjacent clamp. A bracket 136 extending outward from one of the arms 128 carries a cam roll 138, which is arranged to engage a cam plate 140 adjustably secured by a bolt 142 to a rocker arm 144, which is movable around a stationary pivot 146 mounted in the bracket 100. The arm 144 has a lug 148 which bears against an adjustable, spring-pressed plunger 150 mounted in the outer end of the bracket 100 and has also a depending arm 152 connected by a pull spring 154 to a stationary ear 156 upon the bracket 100. A torsion spring 158 surrounding a pin 152 secured in the member 112 by a set screw 151 bears upon a cross web 139 which connects the upper portions of the arms 128 and tends to swing the arms inward and hold the crossbar 130 at the inner end of the clamp, but when the roll 138 engages the cam 140, the crossbar 130 is moved into engagement with the breast of the clamped heel and held there while the arm 144 is moved inward against the tension of the spring 154 until the clamping plate 60 is raised by the cam plate 94, releasing the heel and permitting the spring 154 to contract and

cause the heel to be quickly ejected from the clamp by the crossbar 130.

As the clamp carrier continues to move in the direction of the arrow (Figs. 2 and 3) the cam roll 138 passes off the upper end of the cam plate 140 and engages a cam plate 160 which is affixed to the upper end of one arm 162 of a bell-crank lever which is movable about a fixed pivot 164 mounted in the bracket 100. This bell-crank lever has a second arm 166 which is acted upon by a pull spring 168 fastened to a stationary pin 170 mounted in the bracket 100. The pulling force exerted by the spring 168 upon the arm 166 holds a lug 172, which projects from the side of the arm 162, in engagement with a stop screw 174 which is threaded through a stationary lug projecting upward from the bracket 100. Adjustment of the stop screw 174 will produce a corresponding adjustment of the position of the cam 160 and, consequently, of the position assumed by the cam roll 138, which determines the position of the crossbar 130 in the open clamp. This crossbar 130 is utilized as a breast gage for facilitating the positioning of a fresh heel in the open clamp.

The form in which the heel lifts are assembled, ready to be pressed, is illustrated in Figs. 1, 6 and 7 and comprises a table 180 which is supported upon the machine frame 12. A breast gage 182, against which the breast edges of the lifts are alined, arises from a base plate 184 having a slot 186 through which passes a bolt 188 by which the gage is adjustably secured upon the table 180.

Inclined side jaws 190 are pivotally mounted at 192 in the inner ends of horizontal rods 194 which are held in split clamping sleeves 196 provided with screws 198 by means of which they can be tightened upon the rods 194. Each sleeve 196 is pivoted at 200 in the upper end of an upright slide 202 which may be adjusted vertically in a guide 204 in which the slide may be clamped in adjusted position by a clamping bolt 206. The guide 204 is secured to the table 180 by screws 208.

The bars 194 and the side jaws 190 are sustained by spring-pressed plungers 210 which bear against the under sides of the clamping sleeves 196 and permit the jaws to be depressed into spaces in the table 180 if downward pressure is applied to them. The upper ends of the slides 202 are formed to cooperate with the pivoted clamping sleeves as shown at 212 to prevent the plungers 210 from lifting the bars 194 above a horizontal position.

The outer sides of the lower portions of the jaws 190 bear against surfaces formed at the front portions of guide arms 214 which are pivoted at 216 for horizontal swinging adjustment upon the surface of the table 180. The rear ends of the guide arms 214 carry swiveled nuts 218, engaged by a right and left screw 220 upon which is fixed a collar 222 which engages a notch 224 in the table 180. It will be apparent that turning the screw 220 will effect equal and opposite adjustment of the lower ends of the guides 214 and, consequently, of the jaws 190, to vary the width of the form.

Two rear form jaws 226, similar to the jaws 190, are pivoted at 228 in bars 230 which are mounted in the same manner as are the bars 194. The lower portions of the jaws 226 engage the edges 232 of a forked guide member 234 in the same manner that the lower portions of the jaws 190 engage the guide arms 214. The guide 75

member 234 is slotted at 236 to provide for adjustment longitudinally of the heel form and is held down upon the table 180 by a bolt 238 passing through the slot and screwed into the table.

5 After the lifts are assembled in the form, pressure is applied in the usual manner by the power-operated presser foot 16 and one or more heel-building nails is, or are, driven by the nail driver, or drivers, 18, the power for performing these operations being derived from the main driving shaft 14 which is driven through a clutch or the like controlled by a starting lever 240.

In the operation of the machine the pasted lifts are assembled manually in the heel assembling form F and the starting lever 240 is actuated, with the result that the drive shaft 14 makes one complete revolution during which the presser foot 16 applies pressure to the lifts and the nail driver or drivers 18 drives, or drive, one or more heel-building nails through the lifts. While this is occurring, the shaft 32 is rotated $\frac{1}{2}$ of a revolution, causing a clamp containing a finished heel to be opened by the cam 72 and the heel to be ejected by the bar 130 which is then retracted to gaging position as illustrated in the open clamp in Fig. 2.

The built-up heel which is removed from the form F is placed in this open clamp against the gage bar 130 and the treadle 80 is depressed by the operator, rotating the cam 72 sufficiently to allow the cam roll 70 of the open clamp to pass off the high portion of the cam so that the clamp may be closed upon the heel by the spring 62.

As each heel in the pressing apparatus proceeds around the circuit, it is held uninterruptedly under pressure by the spring 62 during the time required to build eleven succeeding heels which is sufficient to permit the paste to set so that the lifts will adhere permanently to each other.

Having described the invention, what is claimed as new and desired to be secured by Letters Patent of the United States is:

1. A heel-making machine comprising, in combination, heel-assembling apparatus, heel pressing apparatus comprising a series of clamps rotatively mounted beside the assembling apparatus, means adapted to simultaneously operate the assembling apparatus, rotate the clamps and automatically open one of said clamps, and operator-controlled means for closing the opened clamp independently of the other operations.

2. A heel-making machine comprising, in combination, heel-assembling apparatus, heel-pressing apparatus comprising a series of clamps rotatively mounted beside the assembling apparatus, a common drive shaft for operating the assembling apparatus and rotating the series of clamps, means for automatically opening one clamp, while the series of clamps is rotating, each time the assembling apparatus is operated, and operator-controlled means for closing the opened clamp while the series of clamps is stationary.

3. In a heel-making machine, the combination of a rotary carrier, means for rotating the carrier step by step a fraction of a revolution at a time, a series of normally closed heel clamps spaced apart upon the carrier, by distances equal to each step of movement of the carrier, means for automatically opening each clamp when it reaches a predetermined point in the movement of the carrier, and manual means operative to close the open clamp while the carrier is stationary.

4. In a heel-making machine, the combination of a rotary carrier, means for rotating the carrier

step by step a fraction of a revolution at a time, a series of normally closed heel clamps spaced apart upon the carrier by distances equal to each step of movement of the carrier, a normally stationary cam constructed and arranged to automatically open each clamp when it reaches a predetermined point in the movement of the carrier, and manual means for moving said cam sufficiently to permit the open clamp to close while the carrier is stationary.

5. In a heel-making machine, the combination of a rotatively mounted series of spring closed heel clamps, means for rotating said series of clamps step by step, a normally stationary cam constructed and arranged to automatically open each clamp when it reaches a predetermined point, means for moving the cam sufficiently to permit the clamp to close suddenly while said series of clamps is stationary, and a buffer adapted to cooperate with said clamp to absorb the shock resulting from the sudden closing of the clamp.

6. In a heel machine, the combination of a circular rotary carrier, a series of clamp plates mounted thereon, a spider rotatable about the

axis of the carrier, a second series of clamp plates mounted on the spider in cooperative relation to the plates on the carrier to form a series of clamps, and means for effecting relative rotary movement of the carrier and spider about their common axis, whereby all of the clamps are simultaneously and equally adjusted to accommodate heels of the same height.

7. In a heel machine, a heel form comprising a plurality of pivotally suspended heel-engaging jaws the lower ends of which are adapted to swing transversely of the form, guides engaging the lower portions of said jaws, and means for effecting simultaneously equal and opposite adjustment of the guides, to vary the width of the form.

8. In a heel machine, a heel form comprising a plurality of pivotally suspended heel engaging jaws the lower ends of which are adapted to swing transversely of the form, pivoted guide arms engaging the lower portions of said jaws, nuts mounted upon said guide arms, and a right and left screw engaging in said nuts, to effect equal and opposite adjustment of said guide arms and jaws, whereby the width of the form is varied.

FRED ASHWORTH.
